UNITED STATES PATENT OFFICE.

EDWARD C. HAWES, OF PROVIDENCE, RHODE ISLAND, ASSIGNOR TO
GEORGE HAWES & SONS, OF SAME PLACE.

STEAM-TRAP.

SPECIFICATION forming part of Letters Patent No. 340,666, dated April 27, 1886.

Application filed November 3, 1884. Serial No. 147,111. (No model.)

To all whom it may concern:

Be it known that I, EDWARD C. HAWES, of Providence, in the county of Providence and State of Rhode Island, have invented an Improvement in Steam-Traps, of which the following is a specification.

My invention relates to an improvement in that class of steam-traps in which an expansible vessel is employed for closing the steam-inlet opening of the trap; and it consists in the combination of the expansible vessel with a separate valve, whereby the valve may be uniformly closed to its seat without being subject to a one-sided or cramping tendency, as when the side of the expansible vessel or an attachment thereto is made to perform the function of a valve, and in the combination of a removable screw-cap with the head of the adjusting-screw, whereby the screw will be prevented from turning and the steam will be prevented from escaping along the threads of the screw.

Figure 1 is an axial section of a steam-trap provided with my improvement. Fig. 2 is a perspective view of the shoe for the point of the adjusting-screw. Fig. 3 is a perspective view of the valve of the trap. Fig. 4 is an elevation of the outer case with the closing-head removed, showing the supporting-points for the expansible vessel.

In the accompanying drawings, A is the outer case or shell, made in any suitable form and having a head, a, and a flange, b, to which is secured the removable head B by means of the bolts c.

Within the chamber C of the trap is placed the expansible vessel D, which is partially filled with a readily-evaporated fluid, d.

The steam-inlet aperture E is provided with a composition bushing, e, which serves to form a seat for the valve F, which is constructed as shown in Fig. 3, and is adapted to rest at its inner end against the side of the expansible vessel D, so that the said expansible vessel may have a rocking movement without affecting the proper seating of the valve.

The bore of the projecting hub f of the removable head B is provided with a screw-thread adapted to receive the adjusting-screw G, upon the slotted head of which is formed a screw-thread, g, which is adapted to fit the internal screw-thread of the cap H, which serves to cover the head of the screw G and

to form a steam-tight joint around the same, thus preventing the escape of steam along the 55 thread of the adjusting-screw, and also serving to prevent the screw from accidental turning.

The central perforation of the head B at the side adjoining the chamber C is made in rectangular form in order to provide a loosely-fitting socket, l, for the rectangular shank h of the shoe I, which serves to protect the expansible vessel from the wearing action of the point of the adjusting-screw G, the shoe I being prevented from rotation with the rotating screw by means of the shank h and the loosely-fitting holding-socket l.

The expansion of the fluid d within the expansible vessel serves to cause a bulging of 70 the opposite sides of the same, thus closing the valve F to its seat and preventing the escape of steam from the steam-pipes until the gradual condensation of the steam to the form of water has cooled the contained vapor in 75 the expansible vessel sufficiently to cause the valve to be raised from its seat by the over-coming pressure of the steam in the pipes, so as to allow the water of condensation to es-80 cape under the valve and to pass off through the outlet-orifice j of the trap, the operation of opening and closing the valve at the inlet-opening being repeated as often as required to allow the water of condensation to escape from the steam-pipes to which the trap is at-85 tached.

The expansible vessel is to be supported in the chamber C by means of the inwardly-projecting form of the outer case at the points s, which engage with the outer rim of the ex-90 pansible vessel D, as shown in Fig. 4.

I claim as my invention—

In a steam-trap, the combination of the case, the removable head, expansible vessel, the valve, the adjusting-screw having a screw-thread at its head, the bearing-shoe prevented from rotation by means of the angular shank and loosely-fitting holding-socket, and the screw-cap adapted for the screw-thread of the head of the adjusting-screw, substantially 95 as described.

EDWARD C. HAWES.
